UNITED STATES PATENT OFFICE.

GUGLIELMO TANCETTI, OF GENOA, ITALY.

CLEANING DEVICE.

Application filed April 16, 1926, Serial No. 102,527, and in Italy September 30, 1925.

The present invention relates to that type of mopping devices especially adapted for use in connection for the cleaning of car bodies, furniture, or other objects.

- 5 In connection with the construction of such contrivances, it has been customary to fixedly mount the cleaning devices on a suitable handle, tubular or not, and the handle, when tubular, was constructed so as to be
 10 directly fitted to the water hose or other liquid-carrying flexible tube, with or without an intermediary joint, so that when another cleaning instrument was to be mounted on the end of the hose, the main liquid-supply valve had to be previously closed, this operation often requiring the operator to leave the place of operation, in order to stop the flow of liquid, thus causing considerable inconvenience.
 15 The object of the present invention is to provide a suitable mopping device which avoids such inconveniences and saves considerable time as it is constructed in such a manner as to be easily interchangeable with
 20 other cleaning instruments, without the necessity of dismounting the handle piece from the water conducting hose, the single valve-controlled tubular handle being adapted to receive other cleaning instruments.
 25 Another object of the present invention is to provide a mop in which the mopping head is constructed of suitable length, and is mounted on a supporting frame of elongated loop shape, the said frame being adapted to
 30 be readily removed, or to have its fibrous mop changed for other mops, when it has become too dirty or worn out. The construction, further, though giving the mop a very desirable shape, does not permit, however, of
 35 the mop head to accidentally slip from the frame, during use.

An embodiment of the present invention will be described hereinafter, with reference to the accompanying drawings, in
 40 which:

Figure 1 shows an elevation, partly in section, of a tubular handle on which a mop embodying the present invention is fitted.

Figure 2 shows in side elevation, also partly in section, a detail view of the mop shown in Figure 1, without the handle.

Figure 3 is a transverse sectional view taken on line 3—3 of Figure 1.

The handle 1 is in the form of a metallic tube, provided with a frusto-conical ridged mouthpiece at one of its ends, which is

adapted to be fitted to the hose (not shown) and is provided at a suitable point with a control valve 2. To the other end of the tubular handle 1, a sleeve 3 is suitably fastened, the hole in the said sleeve being suitably threaded in order that the threaded nipples of the different cleaning instruments can be screwed therein, in a manner as the mopping device shown, Figure 1.

This mopping device, embodying the present invention, preferably comprises a threaded stem 3', formed integral with, or tightly fastened to a suitable perforated block or sleeve 11 forming a jointing sleeve between the said threaded tube 3 and a hollow delivery tube 12 closed at its free end and provided with a number of small perforations or ports 18 by one of its sides. The sleeve 11 is further provided with two sockets or recesses 11' parallel to and on opposite sides of the central water passage 12', and two radial threaded perforations 13' opening into the said sockets and adapted to receive set screws 14 for fastening the end portions of the mop supporting-frame, 13. This frame is constituted of a looped metallic rod 13, which is suitably constructed of a metallic bar of suitable length, curved at its middle so as to have a U-shaped configuration and the free ends of the U being further suitably curved so as to have at the ends two parallel portions 13' considerably nearer together than the wings of the U. As may be readily seen, this form permits of a very great simplification of construction and, as will be better seen hereinafter, allows a quick and easy dismounting of the mop heads which are thus interchangeable with one another.

The fibrous mopping elements comprise a mass of cotton strings 16 disposed in layers between folded strips of fabric 15, the strips so prepared being cut in lengths slightly greater than the length of the U-shaped supporting frame. The edge portions of the strips are suitably bordered, and after being folded lengthwise to receive the strings 16 are stitched together, so as to leave a tubular part, in which the U-shaped frame is positioned, and if desired the free edges of the fabric strips may be tied together by passing a line or band through the holes 17. The out-projecting cotton strands may also be suitably tied together by a narrow band, so as to form a more compact spongy mass, as shown in Fig. 3.

The free ends of the mop frame 13 are then fitted in the sockets 11 in the sleeve 11 and fastened thereto by means of set screws 14.

5 In operation, the threaded stem of the mopping device is screwed into the sleeve 3 of handle 1, controlled by valve 2, and by opening the said valve, liquid under pressure is sprinkled through small ports 18 in the 10 blind tube 12, towards the spongy mass of strings 16 of the mop head, which thus becomes wet and allows an easy washing of the car body or other device.

Owing to the above construction, the mop 15, 16 and frame 13 are easily dismounted and replaced by other mops, when required, which is very useful when one mop is too dirty or worn out, or also when a supplementary cleaning with mops, either wet with 20 liquids other than water and non-mixable therewith, or also perfectly dry, should be required.

Furthermore, the special form of mop, which is somewhat narrow, and elongated in 25 shape, permits of an easy cleansing of the interstices, etc., while on the other hand it is not possible to adopt for such a form the usual methods of mounting of the mop head on a supporting frame 13 open at its outer 30 end, as in such case the fibrous mop would easily slip away, during the cleansing.

Having thus fully described the invention

what is claimed as new and desired to be secured by Letters Patent is:—

1. A device of the character described, including a fibrous mop fabric having a tubular edge, a U-shaped frame on which the tubular edge of the mop fabric is threaded, a supporting block for removably receiving the ends of the frame, set screws for releasably securing the ends of the frame in the supporting block, the block being provided with a central longitudinal opening, a blind tube engaged with the block and lying between the sides of the frame and 45 having a series of small perforations on the side face of the fibrous portion of the mop fabric, and a threaded nipple extending from the opposite side of the block and in alignment with the longitudinal opening, 50 substantially as and for the purposes set forth.

2. An arrangement as claimed in claim 1, wherein the ends of the U-shaped rod forming the frame project from one end in 55 spaced parallel relation, while the block is provided on opposite sides with the central longitudinal opening with sockets for accommodating said ends of the frame which ends of the frame are adapted to be freely 60 engaged by the set screws so as to be releasably retained in position.

GUGLIELMO TANCETTI.
